UNITED STATES PATENT OFFICE.

GEORGE HOLMES COCKS, OF ASHLAND, KENTUCKY

COMBINATION DRILL-PRESS TABLE AND VISE HOLDER

1,260,513.

Specification of Letters Patent. Patented Mar. 26, 1918

Application filed April 2, 1917. Serial No. 159,255

To all whom it may concern:

Be it known that I, GEORGE H. COCKS,
a citizen of the United States of America,
residing at Ashland, in the county of Boyd
5 and State of Kentucky, have invented cer-
tain new and useful Improvements in Com-
bination Drill-Press Tables and Vise-Hold-
ers, of which the following is a specification,
reference being had therein to the accom-
10 panying drawing.

This invention relates to a combination drill press table and vise holder and has for its principal object the production of an efficient means for supporting a vise and table upon a column of the drill press independently of each other.

Another object of this invention is the production of a combination drill press table and vise holder which has a clamp provided with a gap adjacent which the table is supported thereby permitting the device to accommodate work of a greater size.

A still further object of this invention is the production of a combination drill press table and vise holder wherein the vise and table are mounted upon the column independently of each other, while the vise is capable of vertical adjustment whereby the vise may coöperate simultaneously with the table at different heights although when it is desired to use the table or vise independently of each other the vise may be swung away from the table and lowered if so desired.

35 Another object of this invention is the production of a loosely mounted rack bar which fits upon the shank of the vise and bearing upon the vise, whereby as the rack bar is raised or lowered the vise will be
40 raised or lowered, while the vise will be free to pivot in a horizontal plane at all times.

With these and other objects in view, this invention consists of certain novel combinations, constructions and arrangements of parts as will be hereinafter described.

In the accompanying drawings;—

Figure 1 is a side elevation of the complete combination drill press-table and vise holder showing the vise swinging from the table;

55 - **Fig. 2** is a elevation of a portion of the
081 combination press showing the vice swiveling
adjacent the table whereby the vice is in a
position to grip a piece of work and hold
the same upon the table.

Fig. 3 is a fragmentary perspective view of the upper end of the rack bar:

Fig. 4 is a transverse section taken through the shank of the vise and the rack bar, illustrating the manner in which the rack bar fits upon the shank of the vise.

Referring to the accompanying drawings by numerals, it will be seen that the base 1 of the column 2 is carried upon a support 3. It is of course obvious that this column may be bolted or secured in any other suitable manner to the support 3. The column 2 is provided with an offset portion 4 intermediate its ends thereby providing a gap 5. It will be noted by referring to the drawing that the corners produced by the construction of the gap are arranged so as to improve the strength of the column when the same is in use. It is of course, obvious that the column 2 is provided with a suitable operating mechanism 6, but inasmuch as the invention resides in the construction and mounting of the table and vise, it is not deemed necessary to present a detailed description of the operating mechanism 6.

The bracket 7 is provided with a clamp 8 mounted upon the column 2, this clamp 8 being bifurcated as indicated at 9. It is obvious that this clamp 8 may be held in a clamped set position on the column 2 by the use of a bolt 10, or any other suitable securing means. The sleeve 11 formed upon the outer end of the bracket 7 receives the stem 12 secured to the drill press table 13. This table 13 is carried upon the outer portion of the sleeve 11 as shown clearly in Fig. 1, adjacent the gap 5 formed in the column 2, whereby work positioned upon the table 13, if of a sufficient size may extend into the gap and thus may be accommodated by the drill press. Since the clamp 8 is mounted upon the column 2 of the drill, it is obvious that the table may be swung to one side or the other as desired although the clamp 8 may be retained in a desired set position by the bolt 10 above referred to.

The bracket 14 is provided with a clamp 15 which is releasably retained in a set position by means of the bolt 16. This clamp 15 extends into the bifurcated portion of the clamp 13 as shown clearly in Figs. 1 and 12 08 as to permit the brackets 7 and 14 to be swung adjacent each other when the table 10 is to be used in connection with the device 110 hereinafter described. The sleeve 17 is provided with a journal 18 so as to permit 09

the pinion 19 to be rotatably mounted upon the sleeve 17. The crank 20 is connected to the pinion 19 in any suitable manner so as to permit rotary motion to be imparted 5 to the pinion 19 as the crank 20 is turned in either of two directions. The shank 21 is fixedly connected to the base 22 of the vise and this shank 21 is provided with a round outer periphery as shown in Fig. 4. The 10 rack 23 is provided with a longitudinally extending concaved groove 29, as shown in Fig. 3. This rack fits loosely although snugly upon the shank 21, while the upper end of the rack bears at all times upon the 15 base of the vise. The pinion 19 meshes with the rack 23 and it is therefore obvious that when the pinion 19 is rotated by the crank 20 the rack bar 23 will be raised or lowered. Since this bar bears upon the vise, when 20 the rack moves upwardly the vise will be raised, or when the rack bar is lowered the vise will move downwardly due to its own weight. Since the rack bar is loosely mounted upon the shank the vise will be 25 free to turn or pivot in a horizontal plane, although supported by the bar, whereby the vise may accommodate work under various conditions. The track 24 is mounted upon the base 22 of the vise and bears at one end 30 against the fixed jaw 25 and at its opposite end against the block 26 and the movable jaw 27 is mounted on the track 24 and may be moved in either of two directions by the operation of the bolt 28 which is threaded 35 through the block 26 and engages the movable jaw 27. In this construction it is obvious that the jaw 27 may be moved away from the fixed jaw 25 thereby permitting work of various sizes to be gripped by the vise.

40 When it is desired to use the vise in connection with the table 13 the vise is swung around by the bracket 14 moving with the clamp 15. It is, of course, obvious that the table 13 is normally carried under the drill 45 as illustrated in Fig. 1 and contiguous to the gap 5 formed in the column 2. Therefore it is necessary in order to use the vise with the table, to swing the vise into the position indicated in Fig. 2. At this time the shank 21 may be raised or lowered by the 50 movement of the rack bar by the pinion 19 to move the vise to such a position as to permit the work to rest upon the table 13 and be gripped and positively held in a set position by means of the vise. In this manner the work will be positively held in a desired 55 position so as to be drilled, since the vise will hold the work so operated upon against accidental displacement. If, however, it is desired to use the table or the vise independently of each other the bracket 14 may be 60 swung by the turning of the clamp 15 upon the column 2 to such a position as to permit a considerable space to be between the 65 vise and the table. At this time the vise

may be raised above or lowered below the plane of the table 13 whereby the work may be carried in the vise without interfering with the table.

In devices now in use it is the common 70 practice to mount the vise detachably upon the table or to mount the vise upon an extension projecting from the table and therefore this invention produces a more efficiently operating device capable of a greater 75 latitude of use since the table may be used independently of the vise or the vise may be used independently of the table, as these elements may be moved apart as shown clearly in Fig. 1, or if so desired, the vise 80 may be swung to a point adjacent the table and then may be adjusted for supporting the work to be operated thereon evenly and positively on the table.

What is claimed, is:

1. In a device of the class described, the combination of a column, a table mounted upon said column, a vise movably mounted upon said column whereby said vise may be moved to a point adjacent said table and 90 operated in connection therewith, and said vise be adapted to move away from said table so as to permit either the table or vise to be used independently of each other.

2. In a device of the class described the 95 combination of a column, a table mounted upon said column, a vise movably mounted upon said column whereby said vise may be moved to a point adjacent said table, means for adjusting said vise whereby said 100 vise may be made to hold a piece of work upon said table and said vise being adapted to be moved away from said table when it is desired to use said table or said vise independently of each other.

3. In a device of the class described the combination of a column, a bracket, a clamp formed upon said bracket, and engaging said column whereby said bracket will be positively supported, a sleeve formed upon 110 said bracket, a table carried upon said sleeve, means for holding said table against accidental displacement, a second clamp positioned upon said column, a bracket extending from said last mentioned clamp, a sleeve 115 formed upon said last mentioned bracket, a vise positioned upon said last mentioned sleeve, means for vertically adjusting said vise, said last mentioned clamp being adapted to be turned upon said column 120 whereby said vise may be moved to a point adjacent said table, at which time said vise may be vertically adjusted, whereby a piece of work may be gripped by said vise and held upon said table.

4. In a device of the class described the combination of a column, clamps mounted upon said column, brackets extending from said clamps, sleeves formed upon said brackets, a table carried upon one of said sleeves,

110

115

120

125

130

- a shank extending from the remaining sleeve, a rack bar positioned upon said shank, a pinion rotatably mounted upon said last mentioned sleeve, and said pinion meshing with said rack bar, said pinion being adapted to be rotated, whereby said rack bar may be moved for moving said shank, a vise carried upon the upper end of said shank, whereby when said shank is adjusted 5 may be raised or lowered, thereby raising or lowering said vise, said vise being adapted to turn in a vertical plane without interference from said rack bar, and said vise being adapted to hold work upon said table. 45
5. In a device of the class described, the combination of a column, a bracket having a clamp formed thereon, means for holding 50 said clamp in a set position upon said column, a table supported upon said bracket, a second clamp rotatably mounted upon said column and bearing upon said first mentioned clamp, a bracket mounted upon said last mentioned clamp, and a vise mounted 55 upon said sleeve, whereby said vise may be moved to a point adjacent said table for holding work upon said table.
6. In a device of the class described, the combination of a column, a table mounted upon said column, a vise mounted upon said column adjacent said table, whereby said table 60 may support work while said vise holds the work in a set position. 65
7. In a device of the class described the combination of a column, a table supported upon said column, a sleeve carried by said column, a shank rotatably and vertically movable within said sleeve, a vise carried by said shank, a rack bar having a concaved surface fitting upon said shank and bearing 70 against said vise, a pinion carried by said sleeve and engaging said rack bar, means for turning said pinion, whereby said rack bar 75 may be swung to a point adjacent said table while said rack bar may raise or lower said vise and at the same time permit said vise to be turned in a horizontal plane, thereby allowing said vise to hold work 80 upon said table.

In testimony whereof I hereunto affix my signature.

GEORGE HOLMES COCKS.
